CLAIM

(57) The ornamental design for a portable gun rack, as shown and described.

DESCRIPTION

FIG. 1 is a perspective view of the portable gun rack; FIG. 2 is a top view of the portable gun rack of FIG. 1; FIG. 3 is a side view of the portable gun rack of FIG. 1, both sides being the same; FIG. 4 is a back view of the portable gun rack of FIG. 1, the front and back being the same; and, FIG. 5 is a bottom view of the portable gun rack of FIG. 1. The broken-line disclosure represents portions of the gun rack which form no part of the claimed design.
